CLAIM

The ornamental design for an architectural panel, as shown and described.

DESCRIPTION

FIG. 1 is an upper front right perspective view of a first embodiment of an architectural panel showing our new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is an upper front left perspective view of a second embodiment of an architectural panel showing our new design;

FIG. 8 is a front elevational view thereof;

FIG. 9 is a left side elevational view thereof;

FIG. 10 is a top plan view thereof;

FIG. 11 is a bottom plan view thereof; and

FIG. 12 is a lower side elevational view thereof.

The broken lines in the drawings represent portions of the architectural panel that form no part of the claimed design.

1 Claim, 6 Drawing Sheets
